SOCKET ASSEMBLY FOR A MINIATURE DECORATIVE LIGHT BULB

Joseph M. Ahroni, P.O. Box 3907,
Seattle, Wash. 98124

Filed Apr. 26, 1974, Ser. No. 464,434

Term of patent 14 years

Int. Cl. D13—03

U.S. Cl. D26—1 G

FIG. 1

FIG. 2

FIG. 3

FIG. 4

FIG. 5

FIG. 1 is a side elevational view of a socket assembly for a miniature decorative light bulb embodying my design;

FIG. 2 is a rear elevational view thereof;
FIG. 3 is a front elevational view thereof;
FIG. 4 is a rear perspective view thereof; and
FIG. 5 is a front perspective view thereof.

I claim:

The ornamental design for a socket assembly for a miniature decorative light bulb, as shown.
